(57) **CLAIM**

The ornamental design for a connecting terminal, as shown and described.

DESCRIPTION

FIG. 1 is a front view showing our new design for a connecting terminal;

FIG. 2 is a rear view of the connecting terminal of FIG. 1; FIG. 3 is a right side view of the connecting terminal of FIG. 1;

FIG. 4 is a left side view of the connecting terminal of FIG. 1;

FIG. 5 is a top view of the connecting terminal of FIG. 1; FIG. 6 is a bottom view of the connecting terminal of FIG. 1;

FIG. 7 is a perspective view of the connecting terminal of FIG. 1;

FIG. 8 is another perspective view of the connecting terminal of FIG. 1; and,

FIG. 9 is another perspective view of the connecting terminal of FIG. 1 in use.

The broken lines showing of the device inserted into the terminal in FIG. 9 are included for the purpose of illustrating the environmental structure only and form no part of the claimed design.
